UNITED STATES PATENT OFFICE.

CLARK WAY HARRISON, OF LONDON, ENGLAND.

DESIGN FOR A GAS-LAMP.

No. 40,056.

Specification for Design.

Patented June 15, 1909.

Application filed October 22, 1907. Serial No. 398,682. Term of patent 14 years.

To all whom it may concern:

Be it known that I, CLARK WAY HARRISON, a citizen of the United States of America, residing at 96 Middlesex street, in the city and county of London, England, have invented a new, original, and ornamental Design for Gas-Lamps, of which the following is a specification, reference being had to the accompanying drawing, forming part thereof.

The figure is a perspective view of a gas lamp showing my new design.

I claim:—

The ornamental design for a gas lamp, as shown.

CLARK WAY HARRISON.
